UNITED STATES PATENT OFFICE.

MARSHALL HEDGE PAGE, OF SAN FRANCISCO, CALIFORNIA, ASSIGNOR TO UNITED SALES COMPANY, A CORPORATION OF CALIFORNIA.

SAFETY-VENT

937,713.

Specification of Letters Patent. Patented Oct. 19, 1909.

Application filed December 16, 1908. Serial No. 467,805.

To all whom it may concern:

Be it known that I, MARSHALL HEDGE PAGE, a citizen of the United States, residing at San Francisco, in the county of San Francisco and State of California, have invented a new and useful Safety-Vent, of which the following is a specification in such full and clear terms as will enable those skilled in the art to construct and use the same.

This invention relates to a device used for the purpose of preventing disastrous explosions in receptacles for containing gasolene and other high inflammable liquids of that character.

It is well known that with such substances as gasolene and alcohol benzin and the like that the vapors being continually given off soon produce such a mixture with the air near the gasolene tank as to cause bad explosions, and when the tank is not provided with some means for preventing its utter demolition the explosion of the tank spreads the fire all over the building in which the explosion takes place.

An object of this invention is to provide a device which will be strong enough to hold the inflammable liquid in the tank and yet weak enough to open sufficiently to prevent a bad explosion, and which will prevent the fire from gaining access to the main body of fluid in the tank.

In the drawings, in which the same numeral of reference is applied to the same portion throughout, Figure 1 is a vertical elevation of the device ready for securing to a gasolene or other fuel tank, Fig. 2 is a vertical sectional view of the device, only a portion of the perforations in the lower tube being shown, Fig. 3 is a sectional view of the tube closure, Fig. 4 is a sectional view of the tube top, Fig. 5 is a sectional view of the tube collar, and Figs. 6 and 7 are views of the screens used in the tube closure.

The device is intended to be secured in the opening in the top of a gasolene tank through which the gasolene is fed to the tank, the screw collar 1 holding the safety vent in its place. The tube top 2 has a long tube like screen 3 secured to it by means of the three rivets 4, only two of said rivets showing in Fig. 2, and one in Fig. 1. This tube is of such size and has enough holes in it to permit all the gasolene which may be poured through the hole in the top 2 to at

once pass out into the body of the tank. The top 2 is threaded both internally and externally, the outer threads being for the purpose of carrying the collar 1, and the inner set of threads for the purpose of holding the vent closure 5.

It will be understood by those familiar with the art that it is necessary to fill gasolene tanks through some such opening as is here provided, and the screen 3 is for the purpose of preventing the very rapid burning of the gas, or the probable explosion of the gasolene tank should it happen that the gasolene should be fired during the time the tank is being filled. It will also be understood by those familiar with the art that the gasolene or other liquid fuel in the tank must be under the atmospheric pressure at all times, if the feed is of the gravity system, and then the opening must not be so great as the opening necessary for filling the tank, for the double reason that a smaller opening is all that is required and that a large opening makes the danger from fire greater than with a small opening. This closure is intended to permit the access of sufficient air to allow the proper feeding of the gasolene and at the same time to prevent the waste of gasolene by having the tank exposed to the air over too great an area. The closure 5 is threaded externally for the purpose of securing it in the top 2, and it has a passage entirely through it, said passage being partially closed by means of an annular washer 6 seated on a screen 7 pressed into the passage at the base of the closure, and the disk 8, having a hole therein, secured in the top of the closure by means of a fusible metal, said fusible metal being thickened on one side for the purpose of causing the washer to hold on one side for preventing it from blowing bodily away from the tank, or causing it to "lift off" rather than blow off. Under the disk 8 is another screen which is simply pressed into place, the shoulder on the under side of the top of the closure preventing the screen 9 from being blown out when the disk 8 blows off.

The operation of the device is as follows: The tank being filled with gasolene at the time a fire breaks out near it, the heat will cause more or less of the gasolene to vaporize and on coming from the vent of the tank it will ignite at once, but since the screens prevent the fire from actually flashing back into

the tank the fire burns steadily at the mouth of the tank, but should the heat become great enough the disk 8 will have its fusible metal melted and it will turn over to one side because of the considerable pressure within the gasolene tank and the fire will simply continue to burn, the two screens 7 and 9 cooling the flame enough to prevent ignition of the entire tank of gasolene at one time. The purpose of the upper set of screens is to prevent backfiring of the tank when it might happen to be full to a point above the bottom of the tube, the two top screens preventing the fire from reaching the top of the gasolene and the two screens are prevented from being blown out of the top closure by the shoulders thereon.

Having thus described my invention what I claim as new and desire to secure by Letters Patent of the United States is as follows:

1. In a safety vent for fuel tanks, a collar adapted to be secured to the top of the tank, a screen tube riveted to the collar, a plug 25 having a passage therethrough, said passage being obstructed by means of an annular disk having a fusible metal ring thicker at one part than at others to secure the disk to the plug, and a pair of screens placed at a 30 distance from each other.

2. In a safety vent for fuel tanks, the combination of a collar adapted to be secured to a tank, a screen tube secured to the collar, a plug adapted to be screwed into the collar and having a passage therethrough, said 35 passage obstructed by two annular rings one of which is secured to the plug by means of a fusible metal, said metal being thicker at one place than at all others and two screens placed closely adjacent their re- 40 spective rings.

3. In a safety vent for fuel tanks, the combination of a collar adapted to be secured to a tank, a screen tube secured to the collar, a plug having a passage therethrough, an annular ring placed in said passage at the inner end of the plug, two screens placed in said passage, means to prevent the screens from being forced out of the passage, and a second annular ring secured in the outer 50 end of the plug by means of a fusible metal said metal being thicker on one side of the plug than on the other side.

In testimony whereof I have set my hand this 3rd day of December A. D. 1908, in the 55 presence of the two subscribed witnesses.
